ABSTRACT OF THE DISCLOSURE

An automatic record player that selects and plays one or both sides of a record using a double-headed electromagnet support for the transducer and which has novel record holding, selecting and driving means.

This invention relates to an automatic record player apparatus, and more particularly to an automatic record player apparatus of the type in which a desired record is automatically selected from a number of records arranged in the apparatus and is played.

Accordingly, one object of this invention is to provide an automatic record player apparatus having specific means for automatically selecting a desired record from a number of records placed in the apparatus.

Another object of this invention is to provide an automatic record player apparatus which is provided with a pickup device employing a double-headed electromagnet so as to ensure successive playing of both sides of a selected record.

Another object of this invention is to provide an automatic record player apparatus which is provided with a unit for safely and accurately loading a record on the turntable or easily removing the record therefrom.

Another object of this invention is to provide an automatic record player apparatus in which the diameter of the turntable is selected in accordance with the revolution number of a record to thereby dispense with a speed change mechanism.

Another object of this invention is to provide an automatic record player apparatus in which a record mounted on the turntable can be detachably loaded on a support unit disposed radially on a rotary support disc.

Another object of this invention is to provide an automatic record player apparatus which is provided with specific memory means positioned under a rotary support disc.

Still another object of this invention is to provide an automatic record player apparatus in which a drive source is moved into driving contact with the turntable having mounted thereon a record to revolve the record.

Other objects, features and advantages of this invention will become apparent from the following description taken in conjunction with the accompanying drawings, in which:

In FIGURE 1 reference numeral 1 indicates a horizontal fixed base plate or a deck. The horizontal fixed plate 1 has vertically planted thereon, for example, a shaft 2, and the shaft 2 has rotatably affixed thereto a rotary support disc 3. In this case, the rotary support disc 3 is attached to the shaft at right angles thereto so as to be substantially in parallel to the horizontal fixed plate 1. On the rotary support disc 3 there are arranged radially about its center a plurality of records 4 at equiangular intervals. Reference numeral 5 identifies a boss or a sleeve of the rotary support disc 3. Each of the records 4 is positioned in a plane substantially perpendicular to the rotary support disc 3. In FIGURE 1 reference numeral 6 designates a turntable support unit planted on the rotary support disc 3 substantially vertically thereto, which will be described later on. A turntable 7 having a predetermined thickness is attached to the top of the support unit 6 rotatably about a shaft 8 of the turntable 7, and the record 4 is mounted on the turntable 7 through the use of a suitable attaching device M which will be described later on.

A description will be given in connection with the aforementioned support unit 6. As illustrated in FIGURE 2, a plurality of support posts 103 are disposed on the rotary support disc 3 affixed to the shaft 2 in such a manner as to lie on a suitable circumference about the

shaft 2 radially at equiangular intervals and substantially in a perpendicular direction with respect to the rotary support disc 3. In this case, the free end of each support post 103 has formed in its planar top end portion a bearing groove 104 for receiving the shaft 8 of the turntable 7 at such a location as to be on the same circumference about the shaft 2. On the support post 103 is mounted the turntable of such a construction that the end portion of its shaft 8 may be detachably supported by the groove 104 of each support post 103. The turntable 7 has suitable means and is designed so that the record 4 may easily be mounted thereon and dismounted therefrom, and the size of its driving surface (the outer diameter thereof) is selected to comply with the rated revolution number of the record 4 such as a 45 r.p.m. record, a 33 r.p.m. record and so on. The bearing groove 104 is formed to be a little arc-shaped or both end portions of the shaft 8 of the turntable is so configured as to conform with the arc-shaped groove 104 in its manufacturing process. This ensures stable and accurate holding of the shaft 8 of the turntable 7.

FIGURES 4 and 5 illustrate another embodiment of this invention in which records 4 are placed in a row or in parallel to one another on a support plate 3 and selections of a record to be played is accomplished by reciprocating movement of the support plate 3. That is, both ends of the shaft of each turntable 7 or 7' are fitted into the bearing grooves 104 in such a manner that the record 4 held on the turntable 7 by locking means may assume a position between adjacent support posts 103 vertically planted on the support plate 3. The portion having mounted thereon a required number of records in the manner described just above is referred to as a playing mechanism in this specification. The driving portion of a rubber belt or an idler pressed into driving contact with the driving surface of the turntable is referred to as a driving power transmission mechanism, which will be described later on.

According to the aforementioned turntable support unit, it is possible that the playing mechanism is moved in the axial direction of the turntable shaft 8 to a desired position while the driving power transmission mechanism is fixed. Otherwise, it is also possible that the driving power transmission mechanism is moved in parallel to the axis of the turntable shaft 8 to a desired position while the playing mechanism is fixed.

In the present invention, as has been described above, a turntable having a record easily pivoted to its shaft is picked up and played without the necessity of replacement of records prior to playing as in the prior art. In the case of using a 45 r.p.m. record the record is mounted on a turntable having a shaft the outer radius of which complies with the required revolution number and in the case of a 33 r.p.m. record the record is mounted on a turntable having a shaft the outer radius of which complies with the required revolution number. Therefore, there is no need of providing a special speed change mechanism, with the result that the playing device can be simplified.

The turntable illustrated is rotatably affixed to its shaft, and the shaft is adapted not to rotate when fitted in the grooves of the support posts. However, it is also possible that the turntable and its shaft are formed integrally, the shaft being adapted to rotatably fit in the grooves of the support posts.

FIGURES 6 to 8, inclusive, illustrate the locking means M for releasably locking a record to the turntable 7. Reference numeral 201' indicates a bearing portion for the shaft of the turntable 7, 202 a pair of locking elements mounted on the turntable 7, 203 record locking knobs each fixed to the locking element and provided on the back of the turntable 7, and 204 screws for clamping the locking elements 202 and the record locking knobs 203. Reference numeral 205 designates a spring attached to the locking elements 202, 207 guide grooves

for the locking elements 202, and 208 a fitting portion for the central opening of a record 38φ. In FIGURE 9 reference numeral 4 identifies a record mounted on the turntable 7.

A description will be made in connection with the aforementioned components. As illustrated in FIGURES 6 to 8, inclusive, at least two locking elements 202 are provided on the turntable 7 at locations substantially symmetrical about the shaft 8 of the turntable 7. These locking elements are each adapted to move in a direction of the shaft of the turntable or the periphery of the turntable along the guide groove 207 provided in a radial direction of the turntable. The spring 205 attached to the two locking elements 202 or the locking knobs 203 normally biases the locking elements 202 or the locking knobs 203 toward the periphery of the turntable 7. In inoperative condition the spring 205 presses the locking elements 202 or the locking knobs 203 against the outer side of the guide groove 207. In mounting the record 4 on the turntable 7, the two record locking knobs 203 are pushed towards the shaft 8 of the turntable 7 against the bias force toward the periphery of the turntable 7, and then the central opening of the record 4 is fitted with the fitting portion 208. Upon releasing the pressure applied to the locking knobs 203 with fingers, the action of the spring 205 exerts a clamping force F upon the record 4 in the direction to its periphery and a vertical component N of the force F upon the record 4 toward the turntable 7, since the contact portion of the locking elements 202 with the record 4 is inclined outwardly of the turntable 7, as shown in FIGURES 8 and 12. As a result of this, the record 4 is completely locked to the turntable 7.

In the above example, the spring 205 is a ring-shaped one such as a piano wire but it may be a coiled spring or a plate spring. Further, the shape of the spring is not limited specifically to that shown in the example. In short, the spring 205 is such as performs the function to normally bias the locking elements 202 toward the outer ends of the guide grooves 207. In the foregoing the two locking elements 202 are simultaneously moved, but it is possible that one of the locking elements 202 is adapted to be movable while the other is fixed to the turntable 7. Further, the same results can be obtained, even if the record is clamped by one locking element 202 while the other being dispensed with. In the illustrated example the turntable 7 is formed separately from its shaft 8, but it is also possible that they are formed integrally or that the record opening fitting portion 208 formed integral with the turntable 7 is formed to be of an adapter type separately from the turntable.

The above-described record locking mechanism is simple in construction and easy to handle. Further, since the locking elements are always pressed against the margin of the central opening of the record even while rotating in a vertical plane, no clearance is produced between the record and the locking elements to prevent the disadvantage such as the variations in revolving speed, and in addition, when the reverse side of the record directly facing the turntable is played the record is tightly held on the turntable without coming off from the turntable.

In a stationary memory device 36 of this invention, a pair of conductive discs 9 and 10 are provided, and a plurality of memory elements 11 are disposed between the discs 9 and 10, as illustrated in FIGURE 13. The discs 9 and 10 are spaced apart at a predetermined distance in parallel to each other by a plurality of stanchions 12.

As is clearly shown in FIGURE 14, each memory element 11 is formed of an elongated plate 13 which is preferred to be a magnetic material having a predetermined thickness and the element is configured in such a shape as having stepped portions 14 and 15 in the proximity of its both ends and a pair of stepped portions 16 substantially at its center in its lengthwise direction. Further, one

free end of a ribbon-shaped resilient conductive contactor 17 is fixed to the plate 13 in the vicinity of one end thereof (the stepped portion 15 in the figure) by means of a rivet 18 or the like in a manner so that the contactor 17 extends on one surface of the plate 13 in its lengthwise direction. Meanwhile, the other free end portion of the contactor 17 is bent at right angles and the bent portion is projected out through an aperture 19 bored in the plate 13 in the neighborhood of its center. The projecting portion of the contactor 17 is bent upwards once again, providing a contact portion 17'. In order for such a contactor 17 to make close contact with the plate 13 at all times, it is biased by utilizing its resiliency.

As is apparent from FIGURE 13, in order to engage the upper and lower stepped portions 14 and 15 of each memory element 11 with the pair of discs 9 and 10, a plurality of apertures 20 and 21 are made in the discs 9 and 10 at corresponding locations. The discs 9 and 10 are assembled together with both ends of each of the memory elements 11 being fitted into the corresponding apertures 20 and 21 of the discs 9 and 10 in such a manner as to bridge the discs 9 and 10. In this case, the upper end of each memory element 11 is projected upwardly from the disc 9, and each memory element 11 is arranged so that its face having the contact portion 17' faces the center of the disc 9 and crosses its radial direction substantially at right angles thereto. The apertures 20 of the disc 9 are configured to be a little elongated in the radial direction of the disc 9 so as to ensure that the top end portion of each memory element 11 moves in the radial direction of the disc 9 along the full length of the aperture 20 about the aperture 21 of the disc 10. A washer 22 is interposed between the disc 9 and the upper stepped portion 14 of each memory element 11, and a spring 23 is provided between the disc 10 and the centrally disposed stepped portions 16 of each memory element 11 so as to push up the memory element at all times. Each washer 22 is disposed in suitable frictional contact with the disc 9, which serves to smooth the aforementioned movement of each memory element 11. The spring 23 ensures that each memory element is accurately held at two positions, one being the outermost side of the aperture 20 and the other being the innermost side thereof, and further the spring 23 prevents the memory element 11 from being shifted when subjected to high shock and/or vibration conditions. The contact portion 17' of the contactor 17 projects toward the center of the discs 9 and 10. The apertures 20 and 21 of the discs 9 and 10 are so disposed that the aforementioned memory elements 11 are located on two different concentric circles about the center of the discs 9 and 10 at substantially equiangular intervals corresponding to those of the records 4 arranged on the support disc 3. The number of the apertures bored in each disc is twice as many as that of the records 4 provided on the support disc 3, and consequently the number of the memory elements 11 is naturally twice as many as the records 4. In FIGURE 13 the memory elements 11 on the inner circle are identified at 11' and those on the outer circle are designated at 11 for convenience's sake in description. The apertures 20 and 21 are located in such a relationship that the memory elements 11' on the inner circle are each disposed, for instance, midway between adjacent memory elements 11 on the outer circle.

Further, a disc 24 which is preferred to be of a conductive magnetic material is interposed between the discs 9 and 10. The periphery of the disc 24 has projected therefrom a plurality of projections 25 in a spidery manner, each being opposite to each memory element. Each of the projections 25 has mounted thereon an electromagnetic coil 26. The relationship between each electromagnetic coil 26 and each of the memory elements 11 and 11' is such that upon energization of the electromagnetic coil 26 the memory element disposed opposite thereto is attracted inwardly to the electromagnet corresponding to the energized electromagnetic coil 26 so that

10

20

30

35

40

45

50

55

60

65

70

75

the contact portion 17' of the contactor 17 of the memory element is electrically connected with the end of the projection 25 of the disc 24. Upon deenergization of the electromagnet, the memory element is pulled back outwardly to disengage the contact portion 17' from the disc 24. In this case, it is possible to facilitate the movement of the memory element by the provision of a magnet 27 on the memory element, as shown in FIGURES 13 and 14, so as to ensure good contact of the contact portion 17' with the end of the projection 25 of the disc 24.

The disc 24 is attached to the aforementioned stanchions 12 and is electrically insulated from the disc 10. In order to suitably couple the discs 24 and 9, each stanchion 12 is composed of a first cylindrical support member 28 made of, for example, an insulator material and a second cylindrical support member 29 made of an electrically conductive material. In this case, the second support member 29 has formed at the lower end thereof a diametrically reduced portion 30 capable of being fitted into an aperture 24a of the disc 24, and a hole 31' is bored through the second support member 29 centrally thereof. The first support member 28 has formed therein screw-threads 31 from its upper end to middle point thereof and has projected from its lower end a screw 32. As illustrated in FIGURE 13, a screw 33 made of an insulator material is screwed into engagement with the screw-threads 31 of the first support member 28 through the hole 31' of the second support member 29 while the second support member being interposed between the discs 9 and 24, thus assembling together the discs 9 and 24. Further, the screw 32 of the first support member 28 is projected downwards through a hole of the disc 10 and a nut 34 is threadably engaged with the screw 32 to clamp the disc 10 to the first support member 28, thus assembling together the three discs 9, 24 and 10. Reference numeral 35 designates an insulator such, for example, as a washer, which electrically insulates discs 24 and 10 from each other. In this manner, a fixed memory device 36 of this invention is constituted.

The discs 9, 10 and 24 have centrally disposed apertures 9a, 10a and 24a respectively, through which these discs 9, 10 and 24 are affixed to the aforementioned shaft 2 planted on the stationary part, for example, the support plate 1.

Meanwhile, the underside of the aforementioned support disc 3 has attached thereto two engaging pieces 37 and 37'. In this case, the engaging pieces 37 and 37' are made of an electrically insulating material and are configured in a substantially isosceles triangular shape while having a predetermined thickness, as shown in FIGURE 15. The engaging pieces 37 and 37' are each attached to the underside of the support disc 3 in a manner so that the respective vertexes 38 and 38' defined by the two equal sides of the engaging pieces 37 and 37' are outermost from the shaft 2. Further, the portion of one of the two equal sides of each engaging piece is coated with a conductive film 39 as indicated in FIGURE 15, excepting the portion near the vertex. When the memory element 11 or 11' is in its innermost position, the rotation of the support disc 3 causes the memory element to move into contact with the conductive film 39 of the engaging piece 37 or 37', and further rotation of the support disc causes the memory element to move to its outermost position along the inclination of the side of the engaging piece. Accordingly, the length of each aperture 20 of the disc 9 in the radial direction of the disc 9 is selected to be substantially equal to the difference between a distance R₁ from the face of the engaging piece, for example, 37 on the side of the shaft 2 to the center of the shaft 2 and a distance R₂ from the vertex 38 of the engaging piece 37 to the center of the shaft 2. As a result of this, the portion of the memory element 11 inserted into the aperture 20 can be moved a distance corresponding to that between the base and the vertex of the engaging piece 37.

FIGURE 16 is a connection diagram illustrating one example in which thirty coils 26 and consequently thirty memory elements 11 and 11' are driven. Reference numeral 40 indicates a DC power source for driving the coils 26 and 41 a power source for indicating lamps. Reference characters A to E designate letter selecting buttons, 42a to 42e their respective contacts, and a to f number buttons respectively. The number buttons a to f have each five interlocking change-over contacts (43aa to 43ae), (43ba to 43be), (43ca to 43ce), (43da to 43de), (43ea to 43ee) and (43fa to 43fe). These contacts are normally held in the condition shown in the figure. The thirty coils, namely electromagnetic coils 26 mounted on the projections 25 of the disc 24 (identified by A to E with suffixes a to f in the figure) are connected to the power source 40 through the aforementioned contacts in such a manner as to be energized by pressing the letter buttons and the number buttons corresponding to these coils. Since their connections are well-known in the art and is not related directly to the principles of this invention, no detailed description will be given in this specification. In the example illustrated in the figure, a relay 44 is incorporated in series in a circuit common to the aforementioned coils. Connected to the power source 40 are a series circuit consisting of a credit contact 45 to be closed by putting in the so-called coin, a relay 46 and a normally closed contact 44a of the relay 44, and a series circuit consisting of a normally open contact 46b of a relay 46 and a plunger 47. In parallel to the relay 46 is connected a capacitor 48. Reference numeral 46a represents a self-holding contact of the relay 46, and 46c a contact of the relay 46, which changes over a credit indicating lamp 49 and a stand-by lamp 49'. The plunger 47 serves to hold a selectively pressed letter button in its pressed condition only when the coil 26 is energized.

A description will be made in connection with the operation of the automatic record player apparatus employing the aforementioned circuits and memory device. In FIGURE 1 reference numeral 50 identifies a motor for rotating the rotary support disc 3 and 51 indicates generally a device for revolving the turntable 7. The device 51 will hereinafter be described in detail. In FIGURE 17 showing a plan view of the device of this invention, the turntable 7 has a diameter smaller than that of the innermost sound groove of the record 4. The turntable 7 is formed so that its circumferential surface 7a may be exactly cylindrical about its shaft 8. The turntable 7 is a kind of a shaft to be driven by the device 51 of this invention.

As illustrated in FIGURE 18, the horizontal fixed base plate 1 has planted thereon a support piece 510, to the top end of which is attached to pickup device 59 by a shaft 512. The pickup device will be described later on.

Further, the horizontal fixed base plate 1 has planted thereon a stanchion 413, which carries a motor 414. Reference numeral 415 indicates its rotary shaft and consequently its drive shaft. In the present invention the shaft 8 of the turntable 7 of a record to be played is brought in the same direction as the motor rotary shaft 415.

A driving power transmission mechanism 416 is provided between the drive shaft or the rotary shaft 415 of the motor and the shaft to be driven, namely the turntable 7, and this driving power transmission mechanism 416 is interposed between the selected turntable 7 of a record to be played and the rotary shaft 415 of the motor 414, thus suitably driving the turntable 7. In this case, the relative arrangement of the driving power transmission mechanism 416 to the turntable 7 and to the motor rotary shaft 415 is such that a rotary contact point P₂ between one end of the power transmission mechanism 416 and the motor rotary shaft 415 and a rotary contact point P₁ between the other end of the power transmission mechanism 416 and the turn-

table 7 may be on a tangential line 417 common to the two rotary contact points. The driving power transmission mechanism 416 has a support rod 418 having attached to both free ends thereof, for example, drum-type pulleys 421 and 422 by shafts 419 and 420, and an endless belt 423 of, for example, rubber or the like is stretched between the pulleys 421 and 422. To one pulley 422 is affixed concentrically and integrally therewith a pulley 424 having a greater diameter than the pulley 422. To a shaft 425 provided on the stationary part, for example, on one side of the motor 414, is affixed a rotary arm 426 rotatable about the shaft 425, to the free end of which is rotatably affixed one end of the aforementioned support rod 418 by a shaft 427. In the driving power transmission mechanism 416 illustrated in the figure, the pulley 424 of a great diameter makes direct rotary contact with the motor rotary shaft 415 and the belt 423 stretched between the pulleys 421 and 422 makes direct rotary contact with the circumferential surface of the turntable 7. In this case, the distance between the shafts 419 and 420 is selected such that the rotary contact points P₁ and P₂ are on the common tangential line 417 with respect to the rotary shaft 415 and the turntable 7. Further, the length of the rotary arm 426 is also selected so that when the motor rotary shaft 415 and the turntable 7 are caused to respectively make rotary contact with the driving power transmission mechanism 416 they may be always on the aforementioned points P₁ and P₂ on the common tangential line 417.

Further, a rotary piece 430 is rotatably affixed by a pin 429 to a plated piece 428 on the horizontal fixed base plate 1 and the free end of the rotary piece 430 is caused to engage with a cam 431, coupling the rotary piece 430 with the aforementioned support rod 418 through a driving rod 432. To this end, a projection 432a of the lower end of the driving rod 432 is fixedly engaged with an aperture 430a formed in the rotary piece 430 and an elongated aperture 432b formed in the upper end of the driving rod 432 is engaged with a pin 433 planted on one side of the support rod 418. In this case, the elongated aperture 432b and the pin 433 are adapted to be loosely engaged with each other. The relative arrangement of the driving rod 432 to the support rod 418 is such that when the rotary piece 430 is brought up to its highest position by the cam 431 (which is rotated by other means, though not shown), the support rod 418 is rotated to its highest position by the driving rod 432 to cause the free end of the support rod 418 on the side of the pulley 421 to go away from the margin of the record 4 as illustrated in FIGURE 19 and that when the driving rod 432 is in its lowest position the support rod 418 is caused to assume such a position as shown in FIGURE 18 by the entire weight of the driving power transmission mechanism or by a spring (not shown). In the condition depicted in FIGURE 19 the pulley 424 is slightly moved out of contact with the rotary shaft 415, while the free end portion of the support rod 418 having attached thereto the pulley 421 must be brought up to such a position as to enable rotation of the horizontal rotary disc 3 so as to select a record. For this purpose, the rotary arm 426 has formed therein an elongated aperture 426a, with which the pin 420 of the pulley 424 is engaged, and the support rod 418 is designed so that the side of the pulley 424 is lighter than the opposite side (the side of the pulley 421) with respect to the pin 433 engaging with the driving rod 432. With such an arrangement, when the driving rod 432 is pushed up the pulley 424 of the support rod 418 goes out of contact with the rotary shaft 415 at first and when the support rod 418 is further pushed to a certain height its shaft 420 comes into contact with the upper end of the elongated aperture 426a of the rotary arm 426, with the result that as the driving rod 432 is pushed up further, the side of the pulley 421 of the support rod 418 is greatly

brought up finally to such a position as depicted in FIGURE 19.

The operation of the entire apparatus illustrated will hereinbelow be described. Upon pushing a record selecting button when the apparatus is in its inoperative condition such as shown in FIGURE 19, the horizontal rotary disc 3 is turned to bring a desired record 4 to a position opposite to a pickup arm, after which the cam 431 rotates to bring the driving power transmission mechanism 416 into contact with the circumferential surface of the turntable 7 of the selected record 4 as depicted in FIGURE 18 to rotate it, and substantially at the same time a pickup device 59 is actuated to automatically play the record 4. Upon completion of the play the apparatus is automatically returned to its initial standstill condition such as shown in FIGURE 19.

With such an arrangement as described in the foregoing, since the driving power transmission mechanism 416 is provided which is normally held out of contact with the motor rotary shaft 415 and the turntable 7 but comes into driving contact with them only while in actual use, the pulleys are prevented from deformation which otherwise is likely to result from their constant rotary contact with the turntable. Especially, the driving power transmission mechanism 416 is designed to come into driving contact with the motor rotary shaft 415 and the turntable 7 at the points P₁ and P₂ on the common tangential line 417, and hence it is possible to eliminate the variations in the revolving speed of the record 4 due to the directionality of the power transmission of the driving power transmission mechanism 416 when reversely revolving the motor rotary shaft 415 and consequently the record 4.

In addition, the driving power transmission mechanism 416 is adapted such that the turntable 7 is driven directly by the outer surface of the belt 423, so that even if the pulley 421 is eccentric, no variations in the revolving speed of the turntable 7 are likely to occur. Therefore, the variations in the revolving speed of the turntable 7 can be further eliminated by designing the driving power transmission mechanism such that the outer surface of the belt 423 makes direct contact with the motor rotary shaft 415 while leaving out the aforementioned pulley 424, as illustrated in, for instance, FIGURE 20.

The following will describe the aforementioned pickup device 59 in detail.

In FIGURE 21, reference numeral 502 designates generally a pickup arm. The pickup arm 502 consists of a pair of arm portions 504a, 504b, and a base portion 503. The arm portions 504a and 504b confront in parallel relationship with each other. Cartridges 505a and 505b are respectively attached to the respective confronting surfaces of the arm portions 504a and 504b in the vicinity of their upper ends. Reference numerals 506a and 506b designate styluses which are respectively attached to the respective cartridges 505a and 505b. The styluses 506a and 506b are substantially disposed on the same line and their pointed ends are respectively projected in the opposite directions to each other on the line. In the present specification, for the benefit of explanation, FIGURES 21 and 23 are defined to be front and FIGURES 22 and 24 to be back.

A shaft 507 is attached to the pickup arm 502 at the position substantially intermediate of the pickup arm, for example, to the base portion 503. The direction of the shaft 507 intersects the projecting direction of the styluses 506a and 506b at the right angle. In other words, the direction of the shaft 507 is that from the front to the back in FIGURE 21. Frame 508 is made to be the form so as to surround the base portion 503 of the pickup arm 502. The pickup arm 502 is pivoted to the frame 508 by the shaft 507, whereby the pickup arm 502 can be rotated about the shaft 507 in the projecting direction of the stylus. A U-shaped frame member 511 which surrounds

the frame 508 from its back is attached to the free end of a support member 510. The support member 510 is fixed to the horizontal fixed base plate 1 at substantially right angles thereto.

5 A pair of shafts 512a and 512b are respectively provided on the confronting portions of the frame member 511, the extending directions of the both shafts 512a and 512b intersecting the shaft 507 at the right angle and being substantially horizontal. A pair of projections 512a' and 512b' which are provided on the frame 8 are respectively supported by the confronting ends of the shafts 512a and 512b so that the frame 508 can be rotated about the shafts 512a and 512b.

Furthermore, a driving lever 514 is pivotably attached to the frame 508 by a shaft 513 which is fixed to the one end of the lever 514. To the other end of the lever 514 is attached a driving electromagnet 515 such as a rod-shaped one. In this case, the direction of N and S poles of the electromagnet 515 is selected to be in parallel relation with that of the styluses 506a and 506b. A pair of fixed electromagnets 516a and 516b are respectively attached to the fixed portion, for example, the frame 508 by a pair of supports 516a' and 516b' which are respectively fixed to the frame 508. In this case, the respective electromagnets are dispersed on the line connecting the N and S poles of the driving electromagnet 515 in opposing and spaced relation to the N and S poles of the magnet 515 respectively. To the electromagnets 516a and 516b are supplied DC currents so as to produce the magnetism in one of two electromagnets 516a and 516b the polarity of which is opposite to that of the confronting pole of the driving electromagnet 515 when a DC current is supplied to the electromagnet 515. In this case, the polarity of the magnetism produced in the other electromagnet is the same as that of the confronting pole of the driving electromagnet 515. Accordingly, the driving electromagnet 515 is repelled by one fixed electromagnet, for example, 516b and is attracted by the other, for example, the electromagnet 516a. In this case, it will be apparent that the above condition of the driving magnet 515 for the fixed electromagnets 516a and 516b can be changed by changing the direction of the DC current supplied to the driving electromagnet 515. Accordingly, the lever 514 having the driving electromagnet 515 on its free end portion vibrates in accordance with the vibration of the driving electromagnet 515.

In detailed explanation of fixing the driving electromagnet 515 to the lever 514 a substantially U-shaped frame member 514a is fixed to the free end of the lever 514 and the driving electromagnet 515 is attached to the U-shaped frame member 514a between the confronting free end portions thereof, as apparent from FIGURE 21.

A pair of stylus pressing springs 517a and 517b are provided between the base portion 503 of the pickup arm 502 and the driving electromagnet 515 (in FIGURE 21 between the base portion and the respective free end of the frame member 514a). That is, a pin 518 is fixed to the base portion 503 in the vicinity of the end portion thereof and the respective stylus pressings 517a and 517b are respectively provided between the pin 518 and one of the confronting ends of the frame member 514a and between the pin 518 and the other of the confronting ends. The lever 514 can be rotated to one direction along the projecting direction of the styluses 506a and 506b or to the other direction by the springs 517a or 517b when the driving electromagnet 515 is attracted by one fixed electromagnet or the other, whereby a suitable stylus pressure can be given to the record 4. In this invention, playing the record can be attained by keeping the attracting condition of the driving electromagnet 515 and one of the fixed electromagnets 516a and 516b.

In the present invention, a lever 519 is further attached to the frame 508 by which a switch 520 is closed when playing of the record is completed so that a circuit (not shown) for supplying the currents to the electromagnets

515, 516a and 516b can be opened by the switch **520**. Accordingly, the stylus contacting with the record **4** can be removed therefrom. In addition, the aforementioned pair of the shafts **512a** and **512b** are located on the line passing through the center of the gravity of the portions including the pickup arm **502**, the frame **508** and the like attached to the frame **508** so that unnecessary side pressure applied to the groove of the record **4** through the stylus **506a** or **506b** can be eliminated when playing the record. Reference numeral **521** identifies a balancing weight attached to the lower end of the pickup arm **502** for more effectively removing the unnecessary side pressure.

A pair of substantially parallel levers **522a** and **522b** are attached to the frame **508** from its back, namely levers **522a** and **522b** are pivoted to respective shafts **523a** and **523b**, which are respectively provided on the frame **508**, at their upper portions, as apparent from FIGURE 22. The respective lower free ends of the parallel levers **522a** and **522b** are curved to extend apart from each other, if necessary, and a return spring **524** is inserted between the respective curved ends of the parallel levers for applying a bias thereto so as to approach the free ends of the parallel levers to each other. Pins **525** and **526** are respectively fixed to the frame **508** and the base portion **503** of the pickup arm **502** along the longitudinal center line common to the frame **508** and the pickup arm **502**. A substantially U-shaped support member **528** is attached to the driving electromagnet **515** so as to surround the base portion **503** except the front portion thereof. A pin **527** is fixed to the back of the support member **528** at the middle point corresponding to that between the pins **525** and **526**. The three pins **525**, **526** and **527** are aligned on substantially the same line when the pickup arm **502** is positioned at its non-operative condition as shown in FIGURES 21 and 22. In this condition, between the confronting surfaces of the parallel levers **522a** and **522b** all the three pins **525**, **526** and **527** are held tightly. When the driving electromagnet **515** is driven one of the parallel levers, for example, the lever **522a** is rotated against the biasing force of the spring **524** according to the movement of the pin **527** attached to the driving electromagnet **515** through the lever **528**, as shown in FIGURE 24. In this case, the other of the parallel levers, for example the lever **522b** cannot rotate because of the fact that the pin **525** attached to the frame **508** prevents the lever **522b** from rotation. In this condition, the stylus, for example, **506a** contacts with the one side of the record **4**. Accordingly, playing the record is carried out.

When each electromagnet is deenergized, the lever, for example, **522a** is brought to the initial position due to the force of the spring **524**. Accordingly, the pickup arm **502** is brought to the condition shown in FIGURES 21 and 22. In order to keep the pickup arm **502** at the position where the record **4** is placed along the center between the stylus tips of the styluses **506a** and **506b**, at least one of the pins **525** and **526**, for example, the upper pin **525** is formed to be an eccentric cam, as shown in FIGURE 26, which cam can be rotated about a bolt **525a** for attaching the eccentric cam to the frame, as shown in FIGURE 26 by the dotted line. With such an arrangement, in the condition when the electromagnets **515**, **516a** and **516b** are not energized, the record **4** is brought to the center between the styluses **506a** and **506b** and then the eccentric cam is tightly attached to the frame **508** by the bolt **525a**. Accordingly, the record **4** can be accurately positioned along the center between the styluses after the record is played.

Means for rotating the pickup arm **502** along the plane of the record **4** consist of a pair of lugs **529a** and **529b** attached to the frame **508** and driving elements **530a** and **530b** abutting respectively to the respective lugs, as illustrated in FIGURE 25. The lugs **529a** and **529b** are respectively located at the position upper and lower than the position of the shafts **512a** and **512b**. By respectively driving the driving elements **530a** and **530b** with suitable means, for example, a cam in the opposite direc-

tion with respect to their longitudinal direction, the pickup arm can be rotated to the direction along the side of the record **4**. In the figures, reference numeral **531** designates a so-called oil damper case attached to the frame **508**.

According to the pickup device **59** as explained above, the pair of styluses **506a** and **506b** mounted on the respective cartridges **505a** and **505b** can be changeably contacted with the both sides of the record **4** and which is attained by changing the direction of the DC current supplied to the driving electromagnet.

The pressure of the stylus exerted on the record **4** is easily controlled by adjusting the resiliency of the pair of springs **517a** and **517b**.

In the drawings and their explanation the pickup arm **502** having the two arm portions **504a** and **504b** is explained. However, a rod-shaped pickup arm having a pair of styluses respectively attached to the both opposite planes of the one pickup arm in the vicinity of the free end thereof can be used instead thereof. In this case, the pair of styluses are changeably contacted with two records.

In FIGURE 1 reference numerals **61** and **62** respectively indicate drive control circuits for motors **414** and **50** for the driving device **51** and the rotary support disc **3**. Reference numerals **58** and **60** designate means for controlling automatic operation of the driving device and the pickup device **59** respectively. In the figure components similar to those in FIGURE 13 are identified at 30 the same reference numerals.

In the circuit construction shown in FIGURE 16 closing of a credit switch **45** upon putting in a coin will lead closing of a circuit of the power source **40**—the contact **45**—the relay **46**—the normally closed contact **49a**—the power source **40** (at a time t_0 in FIGURE 27). This energizes the relay **46** to close its self-holding contact **46a** and hence put the relay **46** in its self-holding condition. At the same time, its normally open contact **46b** is closed to energize the plunger **47**. Further, the contact **46c** is so energized by the relay **46** as to light the credit indicating lamp **49** to close a circuit of the power source **41**—the contact **46c**—the credit indicating lamp **49**—the power source **41**, thereby lighting the lamp **49**. As a result of this, the stand-by lamp **49'** is turned out. Pushing a desired letter button, for instance, **A** in such a condition at a time t_1 , the contact **42a** closes and the plunger **47** holds the button **A** in its pushed position. Pushing a desired number button, for example, **a** at a time t_2 , the change-over contact **43aa** closes to constitute a closed circuit of the power source **40**—the contact **46a**—the relay **44**—the contact **43aa**—the coil **Aa**—the power source **40**, thus energizing the coil **Aa**. Consequently, either one of the memory elements **11** and **11'** (shown in FIGURE 13) corresponding to the coil **Aa** is attracted inwardly. In this specification, it is supposed a memory element held in its innermost position is in memorized condition.

Thus, upon feeding a current to the coil **Aa**, the relay **44** is energized to open its normally closed contact **44a**, opening the closed circuit of the power source **40**—the contact **45**—the relay **46**—the contact **44a**—the power source **40**. Meanwhile, the relay **46** is released at a time t_3 dependent upon the time constant determined by the relay **46** and the capacitor **48** connected in parallel thereto. The releasing of the relay **46** leads to deenergization of the plunger **47** and opening of the contact **42a** of the letter button **A** at the time t_3 , thus returning the entire circuits to their initial conditions. The conducting time t_2 to t_3 of the coil **26** can be selected at will in accordance with the capacity of the capacitor **48**.

With the initiation of such memorization of the memory element **11** (at the time t_2), the discs **10** (equal to earth voltage) and **24** are electrically shorted through the contactor **17** of the memory element **11** or **11'**, with the result that the motor **50**, consequently the support disc **3** starts to rotate. When the engaging piece **37** of **37'** turns

into contact with the memory element 11 or 11' held its innermost position (memorized condition) during the rotation of the support disc 3, the memory element is rotated outwardly by the conductive slanting surface of the engaging piece 37 or 37' to cancel the memory of the memory element at a time t_4 and hence stop the rotation of the motor 50 and consequently the support disc 3. The aforementioned pickup device 59 and the turntable driving device 51 are adjusted to play a selected record 4 at such a standstill position of the support disc 3. In such a case, the means 58, 60 and 61 are controlled by the momentary contact (from a time t_4 to t_5) of the conductive film 39 of the aforementioned engaging piece 37 or 37' with the memory element selectively memorized, and the driving power transmission mechanism 51 drives the turntable 7 and consequently the record 4 held thereon. At the same time, the pickup device 59 automatically plays the selected record 4.

By providing the memory elements 11 and 11' on two concentric circles as depicted in FIGURE 13, it is possible that the control means can select which side of the record is played by the pickup device 59 depending upon which memory element is memorized. In this case, both sides of the selected record can be played successively by selection of the same opposing relation of the two engaging pieces 37 and 37' to the memory elements 11 and 11' and by respectively giving memories to two memory elements 11 and 11' corresponding to the engaging pieces 37 and 37'.

In the foregoing the motor 50 is controlled directly by the contactor 17 of each memory element 11 or 11', but it is of course possible that a switch specially provided is driven by the contactor 17 to thereby drive the motor 50.

According to this invention described in the foregoing, if the magnetic plate 24 is formed to be, for example, spiral, it can easily be produced by suitable means such as punching or the like, and further the entire memory device 36 can be constructed only by disposing many memory elements between a pair of discs 9 and 10 while being fitted into the apertures 20 and 21 made in the discs.

Furthermore, many lead wires are led out from the memory device 36 corresponding to the coils 26, but the memory device 36 is fixed to the fixed base plate 1, so that wiring of the lead wires can easily be accomplished. In addition, it is sufficient to mount only two engaging pieces 37 and 37' on the rotary support disc 3, and the conductive film 39 of each engaging piece can easily be connected to external circuits by the use of, for example, a slip ring or the like, though not shown.

It will be apparent that many modifications and variations may be effected without departing from the scope of the novel concepts of this invention.

What I claim is:

1. An automatic record player apparatus comprising a support plate, means for driving said support plate, support means mounted on said support plate, a plurality of turntables rotatably supported on the support means, a plurality of records, mounted on the turntables, selecting means for selecting one of said plurality of turntables and records, a power source, means for driving said selected record, engaging means attached to said support

plate on the side opposite to said support means, and memory means including a pair of spaced plates, a third plate supported between said pair of spaced plates, said third plate formed on the outer periphery thereof a plurality of projections, each of said projections having wound thereon a coil which is excited by said power source in accordance with the operation of said selecting means, a plurality of contactors disposed between said pair of spaced plates, each of said contactors aligned with the outer end portion of each of said projections, one end portion of each of said contactors protruding beyond one of said pair of spaced plates and movable to selectively engage said engaging means, whereby when said selecting means is energized, one of said plurality of coils is excited by said power source to attract the aligned contactor and thereby cause said support plate driving means to drive said support plate, the movement of said support plate causing said engaging means to engage said attracted contactor for operating said record driving means and further movement of said support plate causing the engaging means to disengage from said aligned contactor to stop the operation of said support plate driving means.

2. An automatic record player apparatus according to claim 1 wherein each turntable has a shaft projecting from each side and both end portions of said shaft formed into arc-shaped configurations.

3. An automatic record player apparatus as claimed in claim 2, wherein said record support means has a groove for receiving said shaft, whereby said groove supports a turntable which is arc-shaped.

4. An automatic record player apparatus as claimed in claim 1 wherein the rotational speed of said record may be changed by varying the diameter of the corresponding turntable.

5. An automatic record player apparatus as claimed in claim 1, wherein each of said contactors has a permanent magnet at the position aligned with the outer end of said projection so as to be positively attracted to the corresponding projection.

6. An automatic record player apparatus as claimed in claim 1, wherein the ends of alternate projections of said plurality of projections are formed in a circle and the ends of the other projections formed on another circle and each of said contactors mounted to align with an end surface of said projections.

7. An automatic record player apparatus as claimed in claim 1, wherein said record driving means includes belt driving means and the belt of said belt driving means contacting a selected turntable for rotating it.
